UNITED STATES PATENT OFFICE.

GEORGE F. FENNO, OF SWARTHMORE, PENNSYLVANIA.

METHOD OF SOOT REMOVAL.

Application filed August 4, 1926. Serial No. 127,165.

My invention comprises a new and useful method for removing soot and other deposits from the heating surface of boilers, super-heaters, economizers, air heaters and other chambers and apparatus which usually derive their heat from furnace or flue gases.

The present commercial method usually employed for removing soot from the tubes of the apparatus mentioned above consists of 10 pipes having nozzles thereon distributed throughout the tubes, which direct jets of steam on the surfaces to be cleaned. In the case of boilers particularly, this requires a large number of pipes located in the path of 15 the flue gases where they are subject to rapid deterioration due to the corrosive action of the gases and the high heat to which they are subjected. Furthermore, these distributing pipes have to be connected up with an elaborate system of outside piping for 20 conveying the steam to them. The installation of this piping is becoming more and more difficult due to the large size of modern boilers and to the presence of other apparatus on 25 the boiler walls. Such soot blowers are further limited in their use by the steam pressure available, which frequently necessitates a large number of pipes for supplying the steam jets, and in a case of low pressure boilers often 30 there is not enough steam pressure available to adequately remove the soot.

My invention practically eliminates pipes inside of the apparatus to be cleaned and also greatly reduces the outside piping complication 35 and furthermore makes the operation of the soot blower independent of the pressure available.

Briefly, my invention makes use of the fact that large volumes of gases at high pressure 40 if desired, can be generated by the explosion of suitable chemicals. According to my invention the high pressure is converted into velocity by means of correctly designed nozzles and these nozzles direct the high velocity 45 gases across the heating surface to remove the soot, and furthermore are useful for diverting the normal flow of the flue gases into new channels forming vortexes and eddies which also assist in removal of the soot. In 50 this description the word explosion is used in a very general sense and may be either a quick combination of the chemicals giving a sharp puff, or a slower burning or chemical combination of the chemicals giving a more sustained or prolonged generation of larger vol-

umes of gases; however, the explosion is controlled in respect to character, extent of violence, time of occurrence, and method and place of application.

A typical arrangement of my apparatus 60 suitable for the practice of my invention is shown in the accompanying drawings forming part hereof and in which

Figure 1 is a typical cross section of a water tube boiler showing the arrangement of the 65 water tubes, drums and the like.

Figure 2 is a longitudinal elevation of the same boiler; and

Figures 3 and 4 are top or plan views of 70 nozzles.

In the drawings pipes 1, 2, 3, 4, 5, and 6 are inserted through the boiler wall and terminate in suitable nozzles 13. These nozzles may be of the single type as shown in Figure 75 3 for projecting a single jet of the high velocity gases or they may be fan shaped as shown in Figure 4 for distributing the cleaning fluid over a wider area. Pipes 1, 2, 3, 4, 5, and 6 are connected to headers 10, 11 and 12.

In the practice of the invention by means 80 of the described apparatus the header 10, for instance, is filled with an explosive mixture which can be detonated or fired producing a large volume of gas which is distributed by the pipes 1, 2, 3, 4, 5, and 6 to the nozzles and projected across the surface to be cleaned.

From the above description my method for 85 removing soot will be understood; however, it should be understood that any arrangement of the projecting nozzles and exploding chamber can be used in the practice of the invention to meet the requirements of any particular case. It is immaterial the number of jets that are used, their arrangement, 90 or the method of connecting them to the header. In some applications the gases resulting from the explosion may be simply mixed with the flue gases, the resulting increase in volume causing a sufficient increase 95 in velocity to remove the soot.

Examples of materials are suitable forms 100 of explosive powder, suitable explosive admixtures of air and gas, and suitable chemicals adapted to react with the evolution of 105 gas.

It will be obvious to those skilled in the art that modifications may be made in details of procedure and in matters of mere form 110 without departing from the spirit of the in-

vention which is not limited to such matters or otherwise than as the prior art and the appended claims may require.

I claim:

5. 1. The method of soot removal from heating surfaces which consists in generating large volumes of gases by exploding an explosive mixture, and causing said gases to deflect the normal flow of flue gases producing eddies and vortexes for the removal of soot.
10. 2. The method of soot removal from the heating surfaces of a chamber, which con-

sists in generating a large volume of gas by firing an explosive mixture, and admixing the same with the flue gas to increase the normal velocity of the gases passing through the chamber.

15. 3. The method of soot removal from heating surfaces which consists in producing gaseous jets by the explosion of suitable materials, and applying the kinetic energy of the jets to clean said surfaces by impinging said jets on said surfaces.

20. GEO. F. FENNO.
